UNITED STATES PATENT OFFICE.

BENJAMIN LEWENTHAL, OF NEW YORK, N. Y., ASSIGNOR TO FRED & BEN LEWENTHAL, INC., OF NEW YORK, N. Y., A CORPORATION OF NEW YORK.

DESIGN FOR A RING.

49,094.

Specification for Design.

Patented May 23, 1916.

Application filed April 8, 1916. Serial No. 90,001. Term of patent 3½ years.

To all whom it may concern:

Be it known that I, BENJAMIN LEWENTHAL, a citizen of the United States, residing in the city, county, and State of New York, have invented a new, original, and ornamental Design for Rings, of which the following is a specification, reference being had to the accompanying drawing, forming part thereof.

Figure 1 is a front elevation of a ring, showing my new design; and Fig. 2 is a plan view of the same.

I claim:

The ornamental design for a ring, as shown.

BENJAMIN LEWENTHAL.
